CLAIM

The ornamental design for an electronic package carrier, as shown and described.

DESCRIPTION

FIG. 1 is a perspective view of an electronic package carrier showing my new design;

FIG. 2 is a top plan view thereof;

FIG. 3 is a bottom plan view thereof;

FIG. 4 is a side elevational view thereof, the opposite side being a mirror image of that shown;

FIG. 5 is a front elevational view thereof; and

FIG. 6 is a rear elevational view thereof.

*FIG. 1**FIG. 5**FIG. 6*FIG. 2

FIG. 3

FIG. 4
